UNITED STATES PATENT OFFICE.

THOMAS MCGILL, OF SAN FRANCISCO, CALIFORNIA.

SNOW-MELTING APPARATUS.

1,360,238.

Specification of Letters Patent. Patented Nov. 23, 1920.

Application filed October 9, 1919. Serial No. 329,545.

To all whom it may concern:

Be it known that I, THOMAS MCGILL, a citizen of the United States, residing at San Francisco, county of San Francisco, State of California, have invented certain new and useful Improvements in Snow-Melting Apparatus for Use in Sidewalks and Roadways, of which the following is a specification.

10 This invention relates to an improved snow melting apparatus, the object of which is to provide means whereby the snow may be accumulated in a suitable receptacle and melted therein, from which receptacle it runs to the sewer.

20 The further object of the invention is to provide a receptacle which is capable of being covered over when not in use to allow traffic to pass thereover, but which when in use will have a suitable guard to prevent pedestrians and others from falling into the receptacle and which guard is also used as a handle for the purpose of stirring the mass of snow in the receptacle, to cause it to settle down upon the heating coils and be melted.

25 Another object of the invention is to provide a receptacle for the melting of the snow which will have a screen bottom to prevent dirt and papers from falling into the sewer should such materials be dropped into the snow melting receptacle along with the snow.

30 Another object of the invention is to provide a snow melting apparatus which will have a screen bottom so positioned as to prevent the mass of snow from falling below it so as to keep the sewer connection clean and to provide means whereby the snow may be heated from below. The object of this is to give the water free access to the sewer and eliminate any danger of freezing the mass of snow collected in the receptacle.

35 Other objects of the invention will appear as the description proceeds.

An embodiment of the invention is shown in the accompanying drawings in which the same reference numeral is applied to the same portion throughout, but I am aware that there may be modifications thereof.

Figure 1 is a vertical sectional view of the complete apparatus ready for use.

Fig. 2 is a side elevation of the guard rail and rod used for stirring the snow.

Fig. 3 is a plan view of the guard rails.

Fig. 4 is a plan view of the spider used for supporting the screen and for shaking the snow mass in the receptacle.

Fig. 5 is a plan view of the spider shown in Fig. 4 with the screen in place thereon.

The numeral 1 indicates the side-walk below the level of which the receptacle 2 is installed. In the present instance the sidewalk is of the type in which it is supported other than upon the ground level and the receptacle 2 is supported from the sidewalk by means of suitable angle irons 3 in such number as may be required.

15 The bottom of the receptacle is semi-spherical as indicated at 4 and is connected with the sewer pipe 5. Extending upwardly from the bottom are two legs 6 and 7 which support a bearing 8 upon which the hub of the spider 9 rests. The spider 9 has a hub 10 with two forwardly projecting lugs 11 and 12, in order to enable the street sweeper to rotate the spider sufficiently to jar the snow or shake it down upon the heating coils.

20 Resting upon the spider are a plurality of screens 13 in the present instance eight being used in order to enable them to be readily taken out from the top of the receptacle 2 when the same is to be cleaned. The periphery of the spider 9 rests upon lugs 14 and 15, secured to the receptacle 2 where the semi-spherical bottom 4 joins the sides.

25 Near the top of the receptacle there is a ring 15, which is held in a central position by means of suitable braces 16 and 17, extending to the sides of the receptacle.

30 A wheel 16 with handles 17 and 18 and hub 19 is used for the purpose of preventing pedestrians from falling into the receptacle. This wheel is substantially as large as the top of the receptacle 2 and it is supported by means of a rod 20 to which the wheel is connected by means of its hub and by means of the braces 21 and 22 and said rod extends into the hub of the spider 9. A slot 23 therein receiving the lugs 11 and 12 to enable the spider 9 and its screen plates 13 to be rotated.

35 Extending into the side of the receptacle 2 is a steam pipe 25. This steam pipe has suitable covering 26 and it is connected with a series of coils 27 which coils are provided with openings to allow the escape of steam to melt the snow thrown into the receptacle. The coils are supported by means of brackets

28 and 29 secured inside the receptacle 2 just above the screens 18.

The operation of the apparatus is as follows: The rod 20 may be lifted out of the 5 receptacle completely and the receptacle then covered with an ordinary cast-iron man-hole cover. When the receptacle is to be used, the cover is taken off and the rod 20 is placed in position. The wheel 16 preventing 10 pedestrians from accidentally stepping into the snow receptacle. The snow is then shoveled into the receptacle and is melted by the steam passing from the pipe 25, or if it should pile up therein when 15 melting it may be agitated by turning the spider 9 and thereby caused to drop down upon the steam coils to be melted.

What I claim is as follows, but various 20 modifications may be made in the construction shown in the drawings and above particularly described form, within the purview 25 of my invention.

1. A snow melting apparatus for side-walks and road-ways comprising a receptacle 25 adapted to be sunk below the side-walk level; a screen support in the lower portion of the receptacle, a rod for rotating said screen support and a guard rail connected with said rod above the level of the 30 receptacle to prevent pedestrians from stepping into said receptacle.

2. A snow melting apparatus for side-walks and road-ways comprising a receptacle adapted to be sunk below the level of 35 the side-walk, a heating coil therein, a screen support for the snow below the heating coil, a rod for rotating the screen support, and a handle above the receptacle for rotating the rod.

3. A snow melting apparatus for side-walks and road-ways comprising a receptacle adapted to be sunk below the level of the side-walk, a heating coil therein, a screen support below the heating coil, a sewer connection for the receptacle a rod for rotating 45 the screen support and a guard rail connected with said rod for preventing pedestrians from falling into the receptacle and adapted to be used as a handle for rotating the screen.

4. A snow melting apparatus for side-walks and road-ways, comprising a receptacle adapted to be sunk below the level of the side-walk, a heating coil therein, a screen support for the snow below the heating coil, 55 a rod for rotating the screen support and detachable therefrom, said rod extending above the level of the side-walk and having a guard rail thereon also adapted to act as a handle for rotating the screen.

5. A snow melting apparatus for side-walks and road-ways comprising a receptacle adapted to be sunk below the level of the side-walk, a heating coil adjacent the lower portion of the receptacle, a screen support for the snow below the heating coil, a sewer connection at the bottom of the receptacle, a rod for rotating the screen support and a guard rail connected with said rod above the level of the side-walk.

6. A snow melting apparatus for side-walks and road-ways comprising a receptacle adapted to be positioned below the level of the side-walk, means to support and agitate the mass of snow placed therein, a heating coil in the lower portion of the receptacle and a sewer connection therefor.

THOMAS MCGILL.
